UNITED STATES PATENT OFFICE.

ARTHUR L. STANFORD, OF CHICAGO, ILLINOIS.

RAIL ANCHOR.

1,406,295.

Specification of Letters Patent. Patented Feb. 14, 1922.

Application filed March 10, 1921. Serial No. 451,233.

To all whom it may concern:

Be it known that I, ARTHUR L. STANFORD, a citizen of the United States, residing at Chicago, in the county of Cook and State 5 of Illinois, have invented certain new and useful Improvements in Rail Anchors, of which the following is a specification.

The rail anchor of this invention is designed primarily as an improvement upon 10 the anchors shown in my Patent No. 1,347,301, issued July 20th, 1920, although, the special feature of improvement relates to the means provided for locking the clamping bolt in position on the shank, and the 15 improvement may be employed and utilized in connection with anchors of varying constructions.

Anchors of the type to which the present invention is particularly applied, comprise 20 a jaw member which overhangs one edge of the rail base and is held in clamping position by means of a suitable clip member or the like which engages the opposite edge of the rail base, being held in 25 place by a nut which is threaded onto the anchor shank which underlies the base of the rail. It thus happens that the upper portion of the nut, and the threads on the upper side of the shank are subjected to a 30 shearing stress to which the lower threads are not subjected in like degree, so that it becomes important to provide means for ensuring a wrench tight interlock between the co-acting threads on the upper side of the 35 shank in alignment with the rail base, and the object of the present invention is to ensure such a complete interlock at this point and also provide means for preventing the unthreading of the nut when subjected 40 to the severe vibration incident to the passage of trains over the rail.

Further objects and details of the invention will appear from the description of the invention, which consists in the features of 45 construction hereinafter described and claimed.

In the drawing:

Figure 1 is a side elevation of the rail anchor showing the rail base and the nut 50 in section;

Fig. 2 is a top or plan view of the anchor showing the spring clip omitted and the nut flange struck over to subserve the function of the clip;

Fig. 3 is a detail showing the spring clip 55 of Fig. 1, in place on the shank;

Fig. 4 is a cross sectional view of the threaded end of the shank; and

Fig. 5 is a bottom plan view of the threaded end of the shank. 60

The rail anchor comprises a jaw member 10 provided with a depending forwardly projecting foot 11 adapted to contact a tie at a point considerably below the base of the rail. The jaw member is grooved or 65 channeled on its inner face to afford an upper gripping face 12 and a lower gripping face 13 which converge inwardly, the upper face being obliquely disposed to conform with the obliquity of the upper face of the 70 rail base.

The front portion of the jaw contiguous to the foot 11 is provided with an outwardly extending flange 14 which is reinforced by an outer vertical rib 15 and an intermediate 75 vertical rib 16 and an inner vertical rib 17, the intermediate and inner ribs upstanding from the surface of the upper gripping member and extending longitudinally thereof as shown in Fig. 2. 80

The foot 11 is also reinforced by means of a vertical rib 18 which depends from the lower face of the lower gripping member 13 and extends longitudinally thereof. The rib 18 in conjunction with the lower 85 gripping face 13 merges into a transversely disposed shank 19, which shank at the point of emergence with the jaw member is flattened or widened as indicated at 20, being preferably cored and ribbed on 90 its inner surface to afford the necessary strength and rigidity. The jaw end of the rail anchor above described is quite similar to that described in my Patent No. 1,347,301, and no claim of novelty is predicated on 95 this portion of the structure.

The free end 21 of the shank is rounded and threaded on its upper and lower faces 22 and 23 and flattened on its sides 24 which flattening of the sides is desirable in order 100 to facilitate the casting of the device also to prevent rotation of the clip member now to be described.

In the form shown in Fig. 1, a spring clip member 25 is employed, the same being in 105 the form of a split ring configured to closely embrace the flat sided shank and to slip over the threads on the upper and lower faces

thereof. The free ends 26 of the split spring clip are hooked over to furnish fingers which embrace the edge of the rail base in opposition to the gripping jaw on the opposite 5 side of the rail, and in order to afford a nut locking effect, the spring clip is normally distorted from a true plane as indicated in dotted lines in Fig. 1, so that when the nut is tightly screwed to place, it will 10 exert a pressure which has the effect of flattening out the spring clip and bringing both members of the same into a flat plane of gripping contact with the rail base, thereby holding the nut under spring tension. By 15 flattening the sides of the shank and fitting the spring clip closely thereto, the rotation of the latter is prevented and a more perfect gripping effect is ensured.

Although the presence of the spring clip 20 affords a considerable measure of nut locking effect, nevertheless, it is desirable to afford a more positive lock, and the means provided for securing these results constitute the principal feature of the present 25 invention.

The nut 27 is preferably of collar type and provided with a flange 28 which abuts against the spring clip, and in order to ensure an absolutely tight gripping effect between 30 the shank and the nut, the former on its under threaded face is provided with a thin fin 29, which terminates short of the outer end of the shank as best shown in Fig. 5. This fin constitutes a barrier which 35 bridges the space between the threads, so that when the nut is applied, it will be necessary to employ the force of a heavy wrench to cause the threads of the nut to cut through the fin and this has the effect not only of 40 ensuring a tight interthreading of the nut and shank, but is particularly effective in drawing down the nut into complete engagement with the threads on the upper face of the shank, so that the full effect of the 45 threading will be utilized at a point immediately contiguous to the rail base which is the point subjected to the cross shearing stress when the device is in use, at the same time the cutting of the nut threads through 50 the fin will afford an adequate interlocking to prevent a retraction of the nut when subjected to severe vibration.

This method of ensuring a complete interlocking is particularly serviceable in a device 55 of this character in which the shank threads are cast and are of a relatively coarse character and are at the same time required to withstand a decentered stress which imposes a relatively severe action upon certain portions 60 of the threaded surface.

In Fig. 2, I have indicated an alternate construction in which the spring clip is omitted and the nut flange struck down at a point 30 contiguous to the upper portion 65 of the rail base to overlie the same, and af-

ford a clipping effect and it is obvious that other forms of clips or the like may be employed in lieu of those herein particularly described, in all of which cases, the method applied in the threading of the nut heretofore described are equally available. 70

It will be observed that the fin terminates inside of the free end of the shank which affords means for easily applying the nut to the shank and of screwing it inwardly to 75 a sufficient distance to ensure a substantial grip on the threads before the fin is encountered, after which a heavy wrench will be required to cut through the fin and draw up the nut to its final position. The rail 80 anchor is one which may be cast without any difficulty and applied to the rail without the use of special tools and appliances.

I claim:

1. A rail anchor comprising a jaw member adapted to embrace the flange of a rail, a cross connecting member threaded at its opposite end, a fin on the lower side of the threaded portion, and a nut adapted when screwed to clamping position to cut through 90 the fin, substantially as described. 85

2. A rail anchor comprising a jaw member adapted to embrace the flange of a rail, a cross connecting member threaded at its opposite end, a fin on the lower side of the 95 threaded portion, a nut adapted when screwed to clamping position to cut through the fin, and a clamping member adapted to be engaged by the nut and held against the contiguous rail flange, substantially as 100 described.

3. A rail anchor comprising a jaw member adapted to embrace the flange of a rail, a cross connecting member threaded at its opposite end, a fin on the lower side of the 105 threaded portion, a nut adapted when screwed to clamping position to cut through the fin, and a split spring clamping member having fingers adapted to engage a rail flange in opposition to the jaw member, and 110 being initially distorted from a normal plane and adapted to be forced into a true plane of contact with the rail flange by the screwing up of the nut, substantially as described.

4. In a rail anchor, the combination of a 115 jaw member adapted to engage the flange of a rail, a cross member threaded at its free end and flattened on its sides, a fin traversing the threads on the lower face of the threaded end of the cross connecting member, and 120 terminating short of the extreme end thereof, and a nut adapted when screwed to place to cut through the fin, substantially as described.

5. In a rail anchor, the combination of a 125 jaw member adapted to engage the flange of a rail, a cross member threaded at its free end and flattened on its sides, a fin traversing the threads on the lower face of the threaded end of the cross connecting member, and a 130

nut adapted when screwed to place to cut through the fin, substantially as described.

6. In a rail anchor, a rail gripping member, provided with jaws adapted to embrace the flange of a rail, a cross connecting member provided with threads at its opposite end, a fin extending across the threaded surface, and a nut adapted when threaded in

place to cut through the fin, the fin being so located in position as to cause the nut to be drawn into close engagement with the threads at the upper side and at a point contiguous with the rail flange, substantially as described.

ARTHUR L. STANFORD.
